UNITED STATES PATENT OFFICE

ARTHUR E. SMALL, OF CHICAGO, ILLINOIS, ASSIGNOR TO P. H. MURPHY COMPANY, OF NEW KENSINGTON, PENNSYLVANIA, A CORPORATION OF PENNSYLVANIA

LOAD LIFTING BEAM FOR RAILWAY CARS

Application filed May 28, 1930. Serial No. 456,576.

The device relates to railway freight cars and comprises means forming a part of the roof structure which provides places for attaching load lifting devices, such load lifting devices being used to move heavy articles into and out of the car or move such articles within the car or to place one part of the load over another part, such as double decking automobiles.

10 The connecting member or beam extends longitudinally of the car and is preferably located adjacent the center of the car or may be positioned near the side plate or one near each side plate, or, if desired, may be located 15 in both or in all such positions and still come within the scope of this invention. It may be desirable to raise the load simultaneously from more than one point. The beams may extend the full length of the car and reen- 20 force each and every carline or they may simply include a plurality of carlines and be located as desired. The beams are prefer- 25 ably spaced apart from the roof to provide a space so a chain or rope may be thrown over the beam to support a block and tackle or differential chain or other device.

In the drawings:

Fig. 1 shows a load lifting beam and associated parts of the car.

30 Fig. 2 is a vertical longitudinal cross-section on the line 2—2 in Fig. 1, showing the connection of the load lifting beam of the carline.

Figs. 3, 4 and 5 show modified forms of 35 construction.

The drawings show my improved load lifting device applied to the standard A. R. A. car roof for freight cars, which consists of a channel shape carline 2 comprising substantially vertical walls 3 having lateral flanges 4 at the upper margin of each vertical wall and a plurality of roof sheets secured to said flanges with certain of said sheets overlapping the channel of the carline. This construction forms a box girder so that it is impracticable to attach anything to the walls 3 of the carlines on account of the difficulty of getting at the inside head of a rivet (or the nut of a bolt) to remove or replace it.

50 This is a serious condition in building new

cars and also in repairing cars. Furthermore, makes it quite difficult to apply a load lifting beam to cars already built.

Fig. 1 illustrates the relation of a load lifting beam 7 to the other parts of the car, such as the side plates 10, carline 2, roof sheet 5 and running boards 11.

Fig. 2 shows the load lifting beam 7 comprises a plurality of pipes, the length of each pipe being substantially the same distance as between the centers of adjacent carlines. These pipes pass through apertures in the walls 3 of the carlines and are retained therein by a cotter (20), bolt or similar means which passes through the pipe adjacent each wall of the carline. Fig. 2 shows a stud 21 threaded into the ends of adjacent pipes.

Fig. 3 shows the modification in Fig. 3 the ends of the pipes are threaded and provided with standard collars 23 which are screwed up into engagement with the wall of the carline after the pipe is inserted through the apertures in said wall.

Fig. 4 shows a modified form wherein the end of the pipe is deflected 24 out of alignment to accommodate a sloping wall of a carline.

Fig. 5 shows another modified form where the pipes forming the beam extend through and are supported by both walls of the carline and are connected somewhere between adjacent carlines by the coupling 30 or other similar means.

While I have shown channel shaped beams, it is understood that any other shape beam may be used and still come within the scope of the invention.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a railway car, the combination of spaced apart U-shaped carlines, each having substantially vertical walls with lateral

- flanges at the upper margins thereof, roofing secured to said flanges, a load lifting beam passing through and supported by the adjacent walls of adjacent carlines, and a flanged member at each end of the beam and having a threaded engagement therewith so as to be engaged with the respective walls of the carline so as to prevent the longitudinal movement of said beam.
- 10 2. A railway car construction comprising side plates connected by hollow carlines provided with permanently closed tops, the opposing side walls of adjacent hollow carlines being provided with aligned apertures, a load-lifting beam extending between said adjacent carlines with its ends supported in the openings in the opposing side walls thereof, and means mounted on said beam cooperating with the opposing side walls of said adjacent carlines for preventing endwise movement of said beam relative thereto.
- 15 3. A railway car construction comprising side plates connected by carlines of substantially channel-shaped cross-section provided with sloping side walls having aligned apertures therein and a load-lifting beam extending longitudinally of said car between adjacent carlines with its ends supported in the openings in the opposing side walls of
- 20 30 said adjacent carlines, each end of said beam extending substantially at right angles to the slope of the side wall in which it is supported.
